UNITED STATES PATENT OFFICE.

WARREN V. JOHNSON, OF BLOOMSBURG, PENNSYLVANIA, ASSIGNOR TO AMERICAN CAR AND FOUNDRY COMPANY, OF ST. LOUIS, MISSOURI, A CORPORATION OF NEW JERSEY.

INTERLOCKED MINE-CAR WHEEL AND JOURNAL-BOX.

1,244,739.

Specification of Letters Patent. Patented Oct. 30, 1917.

Application filed January 15, 1917. Serial No. 142,465.

To all whom it may concern:
Be it known that I, WARREN V. JOHNSON, residing at Bloomsburg, Columbia county, State of Pennsylvania, and being a citizen 5 of the United States, have invented certain new and useful Improvements in Interlocked Mine-Car Wheels and Journal-Boxes, of which the following is a full, clear, and exact description, such as will enable others 10 skilled in the art to which it appertains to make and use the same, reference being had to the accompanying drawings, which illustrate the preferred form of the invention; though it is to be understood that the invention 15 is not limited to the exact details of construction shown and described, as it is obvious that various modifications thereof within the scope of the claims will occur to persons skilled in the art.

20 In said drawings:

Figure 1 is a vertical section transversely of a mine car through a wheel and journal box applied to such car;

Fig. 2 is a vertical section taken on the 25 line 2—2 of Fig. 1, showing the coupler annulus in wheel-retaining position and also illustrating, in dot and dash lines, the members of the coupler annulus in position to release the wheel; and

30 Fig. 3 is a side elevation of the journal box showing a means of attaching the coupler annulus thereto.

This invention relates to means for mounting 35 roller bearing or other wheels on axles or shafts so that the wheels may be rotationally retained thereon by an interlocking of themselves with bearings or journal boxes for the axles or shafts.

An application of the invention to running gear for mine cars results in a highly 40 advantageous arrangement in which the wheels of any car equipped with running gear constructed in accordance with this invention may be easily slipped onto or removed from the axles most conveniently. Such wheels may also be retained or released by the simple operation of an 45 complex coupler. Different methods of mounting the coupler will suggest themselves to mechanically skilled persons, but a convenient way will be to pivotally mount the coupler on the journal box or bearing so that it will constitute a hinge-like annulus 50 adapted to have its free ends locked together

and also attached to the journal box or bearing.

Parts of the wheel and journal box may be so formed as to co-act with the coupler annulus to retain the wheel on the axle or shaft without interfering with the free rotation of the wheel.

It is proposed that, when the coupler annulus is unlocked, a member thereof shall automatically open by gravity, while another annulus member shall be manually operable to its open position, and when the members are open they co-act to remain in their open positions, freeing the workman applying or removing the wheel from necessary and annoying attention to the coupling 70 means.

Other features of merit becoming apparent hereinafter are, of course, to be regarded as coming within the scope of the present invention.

Referring to the drawings, in Fig. 1 a portion of an axle or shaft 1 is shown as extending transversely of the mine car body 2, which axle extends through a journal box 3 and projects outwardly beyond the side of 80 the car body 2. Slipped over the outer projecting end of the axle or shaft 1 is a roller bearing wheel 4 having a hollow hub 5 that is provided with a closed outer end 6 and an open inner end, outlined by an annular 85 flange 7.

The outer end of journal box 3 is recessed so that it is provided with an annular flange 8 that extends beyond the outer end wall 9 of journal box 3. The inner flanged end 90 of wheel hub 5 projects into the journal box recess so formed and suitable packing 10 prevents the entrance of dust or grit between the inner end of the wheel hub 5 and the outer end wall 9 of journal box 3. 95

Inserted in the wheel hub 5 is a roller bearing comprising a flanged cylindrical sleeve 11, a roller-positioning annulus 12 retained by the flanges at the inner end of sleeve 11, an end thrust bearing member 13 100 retained by the flanges at the outer end of sleeve 11 and a plurality of cylindrical rollers 14 which have trunnions at their opposite ends adapted to travel in annular channels or guideways 15 and 16 on the inner faces 105 of end thrust bearing member 13 and annulus 12, respectively. The entire roller bearing assembly is conveniently locked

within wheel hub 5 by any suitable means such as a bolt and nut 17, the head of the bolt being countersunk in the bearing member 13 and the bolt shank extending 5 through the outer wall 6 of wheel hub 5 and having applied thereto a suitable nut.

Outer end wall 6 of wheel hub 5 is perforated and threaded for the reception of a plug 18, the removal of which plug presents 10 an opening for the entrance of lubricant. The lubricant is adapted to pass through apertures 19 in end thrust bearing member 13 and to be delivered to the cylindrical rollers 14. Said rollers carry and 15 wipe the oil about the outer end of axle or shaft 1 along which the lubricant is entrained so that it may pass into and lubricate the bearings in the journal box 3.

As best shown in Fig. 3, a boss or protuberance 20 extends from each side of the annular flange 8 of the journal box 3, and, as indicated in Fig. 2, the protuberances 20 are diametrically opposed.

A coupler comprising, preferably, a pair 25 of similar substantially semi-circular members, is attached to one of the protuberances or bosses 20, in what is in effect a permanent manner, by a pivotal means, such as a bolt 21. The shank of said bolt passes, 30 through apertures in the fulcrumed ends of the upper and lower coupler members 22 and 23, extending through one of the bosses 20 and projecting rearwardly beyond the outer end wall 9 of journal box 3. A nut 35 or collar 24 is applied to the projecting end of bolt 21 and may be held against withdrawal by the insertion of a cotter pin 25 through the shank of bolt 21 outside of nut or collar 24.

As may be observed in Fig. 2, the free 40 ends of the upper and lower semi-circular coupler members 22 and 23 are also provided with perforations which are adapted to register with each other and with a hole 45 in the boss 20 that is diametrically opposed to the center of rotation of coupler members 22 and 23, when said members are in their closed positions, as indicated in full lines in Fig. 2.

Another bolt 21 passes through the 50 apertures in free ends of upper and lower coupler members 22 and 23 and through the boss with which they are associated, the inner end of the shank of this bolt being 55 provided with a nut or collar 24 which, as before, may be definitely retained in place by a cotter pin 25.

It is to be seen in Fig. 1 that the width 60 and disposition of the semi-circular upper and lower coupler members 22 and 23, when they are in their closed positions, is such that they project above and below the inner and outer annular faces of flange 8. The internal diameter of the thus formed retaining-coupler annulus is less than the ex-

ternal diameter of the flange 7 at the inner end of hub wheel 5, so that while wheel 4 is adapted to freely rotate it cannot release itself from the outer end of axle or shaft 1. Coupler annulus members 22 and 23 being securely fastened to diametrical points on the outer end of journal box 3, resistance to the separation of the wheel hub 5 from the journal box is adequately great. Also, there will be no excessive end thrust by axle or shaft 1 tending to disrupt the connection between said wheel and journal box 3, there being a collar 26 on said axle or shaft adapted to abut the inner end of journal box 3 and to modify the end thrust of said axle against the end thrust bearing member 13.

When the wheel is first applied to the projecting end of shaft 1, or whenever it is desired to remove a wheel that has been in 85 service, one of the bolts 21 is removed, according to which is most convenient. In the drawings, this has been indicated in Fig. 2 as the bolt at the right, and after the cotter pin 25 and collar or nut 24 associated with that bolt have been removed and the bolt itself withdrawn, the lower coupler member 23 will swing by gravity to approximately the position indicated in Fig. 2. The upper coupler annulus member 22 is operated manually to be swung to the position indicated in Fig. 2. As clearly shown in Fig. 3, a shoulder 27 is provided near the opposite ends of upper coupler annulus member 22, preferably by bending 90 outwardly the lower ends of member 22 which lap corresponding ends of the lower coupler annulus member 23.

When upper annulus member 22 is swung to its open position, one of the shoulders 27 will encounter the outer edge of lower coupler annulus member 23 and rest thereupon so that said upper coupler annulus member 22 will lie in an open position. It will thus be seen that, under the influence of gravity, 100 both members of the coupler annulus are held in their open positions, making it very convenient to apply or remove the wheel 4.

It will, of course, be understood that the fulcrumed ends of the semi-circular coupler members 22 and 23 may be more permanently retained by substituting a rivet for the bolt 21 that pivots them to journal box 3. It is, however, optional with the manufacturer whether he will use a rivet 110 connection or that illustrated.

What I claim is:

1. In combination, a journal box, an axle passing therethrough, a wheel mounted on said axle having a portion telescoping with 125 said journal box and a coupler comprising a plurality of rotatably anchored members and means locking said members against but operable to permit rotation of said members, said coupler preventing or permitting 130

separation of said journal box and wheel according to the positions of said members.

2. In combination, a journal box, an axle or shaft projecting therefrom, a wheel mounted on said axle or shaft adjacent said journal box and a coupler comprising a plurality of pivoted members and means for locking said members in such relation to said journal box and wheel as to prevent separation thereof, said members being operable to permit separation of said journal box and wheel.

3. In combination, a flanged journal box, an axle or shaft having a bearing therein, a flanged wheel mounted on said axle or shaft adjacent said journal box and a coupler comprising a plurality of pivoted members and means so relating said members to the flanges of said journal box and wheel as to prevent separation of the last two mentioned elements, said members being capable of rotary movement to permit the separation thereof.

4. In combination, a journal box, an axle or shaft having a bearing therein, a wheel mounted on said axle or shaft and a coupler secured to said journal box comprising a plurality of members adapted to be arranged to co-act with said journal box and wheel to retain the latter on said axle or shaft, some of said members being adapted to be moved without disconnection from said journal box to positions whereby said wheel may be removed from said axle or shaft.

35 5. In combination, a journal box, an axle or shaft bearing therein, a wheel mounted on said axle or shaft and a coupler pivotally connected with the journal box and comprising a plurality of members adapted to co-act with said journal box and wheel to retain the latter on said axle or shaft and means preserving such co-action, said members being adapted under the influence of gravity to be retained in positions permitting the withdrawal of said wheel from said axle or shaft.

6. In combination, a journal box, an axle or shaft bearing therein, a wheel mounted on said axle or shaft and a coupler pivotally connected with the journal box and comprising a plurality of members adapted to co-act with said journal box and wheel to retain the latter on said axle or shaft, one of said members being operable by gravity and another thereof being operable manually to cause both members to mutually react and be held in positions permitting the withdrawal of said wheel from said axle or shaft.

60 7. In combination, an axle or shaft, a bearing therefor, a wheel mounted on said axle or shaft and a coupler comprising a plurality of members adapted to co-act with said bearing and wheel to retain the latter on said axle or shaft, said members being

operable one by gravity and another thereof manually to permit the release of said wheel from said axle or shaft, said members being adapted to coöperate to remain in wheel-releasing positions.

70 8. In combination, a wheel having a hub flanged near one end, an axle entering said hub, a roller bearing in said hub receiving said axle or shaft, a journal box through and beyond which said axle or shaft projects, means on said axle or shaft limiting such projection of the same and a coupler comprising members adapted to swing embracing the flanged end of said hub and coöperating therewith and with said journal box to retain said wheel on said axle or shaft.

75 9. In combination, a journal box, an axle or shaft bearing therein, a wheel having a hub mounted on said axle or shaft and a coupler comprising a plurality of rotatable members, means pivotally mounting the same and means for locking the free ends of said members, the latter when locked forming an annulus coöperating with said wheel hub and journal box to retain said wheel on said axle or shaft.

80 10. In combination, a journal box, an axle or shaft passing through and beyond the same, a wheel mounted on said axle or shaft having a flanged hub portion extending into said journal box and a coupler comprising a pair of rotatable members, means pivotally mounting the same on said journal box and removable means locking said members to said journal box to form an annulus 100 adapted to coöperate with said flanged wheel hub portion to retain said wheel on said axle or shaft, said members being rotatable to wheel-releasing positions.

85 11. As an article of manufacture, a coupler comprising a plurality of rotatable members, means making a hinge-like connection therebetween and adapted for connection to a support, said members having free ends adapted to be brought into propinquity to form an annulus that is adapted to coöperate with the indicated support and a wheel to cause the latter to be retained on an axle or shaft and means for locking the free ends of said members together adapted 110 for connection to the support, said members being adapted to be opened to release the wheel.

105 12. As an article of manufacture, a coupler comprising a pair of rotatable members, means making a hinge-like connection therebetween and adapted for connection to a support, said members having free ends adapted to be brought into propinquity to form an annulus that is adapted to coöperate with the indicated support and a wheel to cause the latter to be retained on an axle or shaft and means for locking the free ends of said members together adapted for connection to the support, one of said members 120

being adapted by gravity and the other thereof by manual operation to be opened to release the wheel.

13. As an article of manufacture, a coupler comprising a pair of rotatable members, means making a hinge-like connection therebetween and adapted for connection to a support, said members having free ends adapted to be brought into propinquity to 10 form an annulus that is adapted to coöperate with the indicated support and a wheel

to cause the latter to be retained on an axle or shaft and means for locking the free ends of said members together adapted for connection to the support, one of said members being adapted by gravity and the other thereof by manual operation to be opened to release the wheel, said members co-acting to remain in open positions. 15

In witness whereof I have hereunto set 20 my hand.

WARREN V. JOHNSON.
